HIGH BAY LIGHTING UNIT

Warren Sherwood Lum, Warners, and Bjarne Netland,
Liverpool, N.Y., assignors to Crouse-Hinds Company,
Syracuse, N.Y., a corporation of New York

Filed Oct. 12, 1966, Ser. No. 4,252

Term of patent 14 years

(Cl. D48—23)

FIG. 2

FIG. 3

FIG. 5

FIG. 6

FIGURE 1 is a front elevational view of a high bay lighting unit embodying our new and original design. The rear side of the unit is a mirror image of the front elevational view.

FIGURE 2 is a side elevational view looking to the right, FIGURE 1. The opposite side of the unit is a mirror image of the side shown in FIGURE 2.

FIGURE 3 is a top plan view.

FIGURE 4 is a sectional view taken on line 4—4, FIGURE 1.

FIGURE 5 is a sectional view taken on line 5—5, FIGURE 1.

FIGURE 6 is a sectional view taken on line 6—6, FIGURE 1.

We claim:

The ornamental design for a high bay lighting unit, as shown and described.
